(57) **CLAIM**

The ornamental design for a solar lamp, as shown and described.

DESCRIPTION

FIG. 1 is a top perspective view of a solar lamp incorporating the new design;

FIG. 2 is another top perspective view thereof;

FIG. 3 is a side perspective view thereof;

FIG. 4 is another side perspective view thereof;

FIG. 5 is front view thereof;

FIG. 6 is a back view thereof;

FIG. 7 is an enlarged view thereof;

FIG. 8 is a bottom view thereof;

FIG. 9 is a side view thereof; and,

FIG. 10 is another side view thereof.

The broken lines in the drawings depict portions of the solar lamp that form no part of the claimed design.
